AIR CLEANER

Edward N. Jacobi, Milwaukee, Wis., assignor to
 Briggs & Stratton Corporation, Milwaukee,
 Wis., a corporation of Delaware

Application June 6, 1945, Serial No. 597,825

9 Claims. (Cl. 183—15)

1

This invention relates to air cleaners and has particular reference to cartridge type cleaners in which the air to be cleaned is first passed through a body of oil or other suitable fluid.

Air cleaners of this general type usually comprise a housing formed jointly by a pair of axially separable cup-like casing members with their open ends substantially telescoped together to enclose a filter cartridge supported in the upper portion of the housing and through which the air to be cleaned flows after first passing through a quantity of oil or the like contained in the lower casing section.

The lower outer portion of the cartridge is adapted to be immersed in the oil contained in the bottom of the lower casing section and it is customary to mount cleaners of this type in an upright position with the bottom of the lower casing section resting on a vertically disposed carburetor inlet duct, with a discharge port for cleaned air in the bottom wall of the lower casing section communicating with the carburetor inlet duct.

One of the objects of the present invention resides in the provision of an air cleaner of the character described which is of extremely simple construction to enable manufacture and assembly thereof at low cost.

Another object of this invention resides in the provision of a novel unitary cartridge for air cleaners of the character described having a central air duct extending through the body of filter material therein and adapted to seat on the upper end portion of an upstanding discharge tube in the lower casing section so as to act as an extension of the discharge tube, with the central air duct so connected with the outer shell of the cartridge that force exerted on the upper edge portion of the outer shell by the upper casing section in a direction to draw the casing sections together is transmitted to the lower end of said central duct to aid in sealing the duct with respect to the standpipe.

More specifically, it is an object of this invention to provide a novel cleaner cartridge comprising an outer shell the lower end of which is adapted to be immersed in a body of oil or other fluid, an inner tubular member forming a portion of an air discharge duct, and circumferentially spaced substantially radial ribs or struts clinched in the side wall of the shell and extending inwardly for connection to the tubular member adjacent to the lower end of the shell.

A further object of this invention resides in the provision of a novel cleaner cartridge of the

2

character described having sealing rings secured thereto at opposite ends thereof, with one of the sealing rings overlying the upper end portion of the outer shell of the cartridge and the other sealing ring carried by the inner tubular member of the cartridge at the opposite end of the shell.

Still another object of this invention resides in the provision of a cleaner cartridge of the character described having means thereon for guiding the same into position within its enclosure and for holding the cartridge axially aligned with the casing sections forming the enclosure.

With the above and other objects in view which will appear as the description proceeds, this invention resides in the novel construction, combination, and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is an elevational view of the air cleaner of this invention with parts thereof broken away and shown in section to illustrate the interior construction thereof; and

Figure 2 is a cross sectional view taken on the plane of the line 2—2 of Figure 1.

Referring now more particularly to the accompanying drawing in which like numerals indicate like parts, the numeral 5 generally designates the air cleaner of this invention.

The cleaner comprises a housing or enclosure 6 formed jointly by upper and lower casing sections 7 and 8 respectively of substantially cup-like shape and having their open ends substantially telescoped together as shown in Figure 1. The rim 9 of the upper casing section has a larger diameter than the rim 10 of the lower casing section so as to define an annular space 11 between the sides of the casing sections through which air enters the enclosure.

The lower casing section 8 has a central standpipe 12 projecting up from its bottom wall 13 toward the rim 10 of the section. The standpipe 12 opens through the bottom wall 13 of the casing section 8 so as to provide for the discharge of cleaned air from the housing, and its upper extremity is curled over as at 14 to provide an annular seat for the cartridge as will be later described.

A body of oil 15 or other suitable liquid is contained within the lower casing section to a depth slightly beneath the rim or seat 14 of the standpipe.

The cartridge 18 of this invention is received within the upper portion of the housing formed by the upper and lower casing sections and comprises a cylindrical shell 19 within which is contained a body of any suitable filter material 20. Extending centrally through the body of filter material is an inner tubular member 21 coaxial with the outer shell 19 and joined thereto by means of a number of substantially flat ribs like spacing struts 22 extending radially between the tubular member and the shell and located at circumferentially spaced points about the axis of the cartridge.

The outer marginal portions 23 of these struts, of which there are at least three, are clinched between the side walls of longitudinal folds 25 struck outwardly from the shell 19 and projecting from its exterior. These longitudinal folds act to stiffen the outer shell 19 and enable the same to be made from a rectangular blank of relatively light sheet metal in which the crimping for the folds 25 is performed prior to rolling the blank into cylindrical shape.

The ends of the blank are joined by an outseam 26 having a shape similar to the folds 25 to enable reception of the outer marginal portion 23 of one of the radial spacing struts 22 for clinching therein.

As clearly shown in Figure 1, the radial spacing struts 22 extend from the upper portion of the shell downwardly and substantially diagonally inwardly to have their inner extremities 27 disposed alongside the lower extremity of the inner tubular member 21. The lower extremity of the tubular member is provided with an annular shoulder 28 in the form of a bead pressed outwardly from the wall of the tubular member and located a short distance inwardly of its lower extremity. It will be noted that the lower extremity of the tubular member is of a diameter to enable the same to enter into the interior of the rim 14 at the upper end of the standpipe.

A sealing ring 29 in the nature of a fiber gasket is received on the lower extremity of the tubular member 21 with its upper face disposed against the shoulder 28 and its opposite side facing the extremity of the tube. This gasket is maintained in position on the tubular member against the shoulder 28 by means of jaws 30 and 31 formed on the inner extremities of each of the radial spacing struts 22 and which jaws embrace the shoulder and the sealing ring to hold the ring firmly against the shoulder and to secure the tubular member 21 assembled with the shell 19.

The cartridge is installed within the enclosure by seating the gasket 29 on the rim 14 of the standpipe, and axial alignment and hence communication between the standpipe and tubular member 21 assured by engagement of the lower jaws 31 of the radial spacing struts 22 with the exterior of the standpipe at the upper end portion thereof. The tubular member 21 thus forms an upward extension of the standpipe 12 with the gasket 29 providing an air-tight seal therebetween.

With the cartridge in the position described, it will be noted that the oil level is beneath the seal effected at the juncture of the ring 29 with the rim 14 of the standpipe and that the outer shell 19 projects downwardly into the lower cas-

ing section 8 sufficiently far as to be immersed in the body of oil contained therein.

The upper casing section 7 rests on the upper edge of the shell 19 of the cartridge and to prevent leakage of air past the cartridge a sealing ring or gasket 34 is interposed between the bottom wall 35 of the upper casing section and the upper end portion of the shell 19.

The washer 34 also rests on the upper ends of the struts 22 to receive support therefrom with lugs 36 on the radial struts 22 extending over the inner edge portion of the washer to hold the same assembled with the cartridge. The gasket 34 upon drawing of the casing sections together provides an air-tight seal between the upper end of the outer shell 19 of the cartridge and the closed or bottom wall 35 of the upper casing section.

In addition, drawing of the casing sections together exerts an axial force on the shell 19 of the cartridge which is transmitted downwardly and inwardly through the diagonally extending spacing struts 22 to the lower portion of the tubular member 21 to press the sealing ring 29 thereon firmly against the rim 14 of the standpipe to assure an air-tight seal between it and the tubular member.

This construction distinguishes from constructions used in many past types of cleaners wherein drawing of the casing sections together directly imposed an axial force on the tubular member to effect sealing thereof with the standpipe.

Besides holding the washer 34 assembled with the cartridge, the lugs 36 on the upper extremities of the radial struts 22 also act to center the upper casing section 7 with respect to the cartridge and lower casing section 8. For this purpose, the bottom wall 35 of the upper casing section is stepped to provide a substantially cylindrical wall portion 35' against which the lugs 36 engage to hold the upper casing section coaxial with the cartridge.

In the present cartridge it is to be noted that the inner tubular member does not project outwardly of the open upper end of the cartridge so that a space exists between the upper end of the tubular member and the bottom wall of the upper casing section 7. It is also to be noted that in the present construction the bottom wall of the upper casing section 7 acts as a closure for the open top of the cartridge with the side walls of the upper casing section providing an eave to prevent dirt or moisture from entering the space between the side of the lower casing section and the filter cartridge.

The filter material 20 is retained in position within the cartridge by means of screens 37 and 38 at the opposite ends of the cartridge and extending radially between the inner tubular member and the outer shell 19.

In the installation of the cleaner of this invention the bottom casing section 8 is placed over the upright air intake duct 40 of the carburetor, which it will be noted, may extend upwardly a distance into the interior of the standpipe 12, and a sealing ring or gasket 41 is positioned between the bottom wall 13 of the lower casing section and a supporting flange 42 formed on the duct 40 a short distance below its upper extremity.

The customary tie rod 43 which has its lower end anchored to the duct 40 in the usual manner extends upwardly axially through the intake duct 40 and the discharge duct formed jointly by the standpipe 12 and the inner tubular member 21 and passes out through the enclosure through an

aperture 44 formed centrally in the bottom wall 35 of the upper casing section.

The upper end of the tie rod is threaded as at 45 to receive a wing nut 46 thereon which may be brought to bear against the bottom wall of the upper casing section to firmly hold the cleaner assembled on the carburetor inlet duct 40 with the casing sections tightly drawn together. In this manner the cartridge is effectively sealed against the upper casing section and has its tubular member 21 adequately sealed in communication with the standpipe 12.

Hence, it will be apparent that air entering the cleaner is caused to flow upwardly into the annular space 11 and thence downwardly between the side wall of the lower casing section and the shell 19 of the cartridge to pass through the body of oil 15 before passage through the filter material 20 and entry into the upper open end of the inner tubular member 21.

If desired, the inner tubular member 21 may also be formed into a tube from a substantially rectangular blank of sheet metal. The ends of the blank thus rolled up are butt welded together as at 40 to provide a rigid tubular construction reinforced by the bead 28 which is preferably formed in the blank prior to rolling the same into tubular form.

Attention is also directed to the fact that the longitudinal folds 25 act to guide the cartridge into its proper position within the lower casing section inasmuch as the lower jaws 31 on the radial spacing struts 22 are not immediately engaged with the upper extremity of the standpipe 12 upon installation of the cartridge.

From the foregoing description taken in connection with the accompanying drawings, it will be readily apparent to those skilled in the art that this invention provides an air cleaner of exceptionally simple nature capable of being manufactured at low cost.

What I claim as my invention is:

1. An air cleaner of the character described comprising: a housing including substantially coaxial upper and lower cup-like casing sections having their open ends facing each other and spaced apart to provide an annular air inlet for the cleaner; a tube projecting axially upwardly from the closed end of the lower casing section and opening therethrough to provide for the discharge of cleaned air from the housing; a cleaner cartridge within the upper portion of the housing including an annular outer shell concentric to but spaced from the sides of the casing sections and having its upper end portion seated against the closed end of the upper casing section, a tubular member providing an axial air passage through the center of the cartridge in line with the discharge tube and having its lower end received on the upper end of the discharge tube so as to be supported thereby, said tubular member providing an upward extension of the discharge tube, circumferentially spaced struts extending diagonally between the upper end portion of the shell and the lower portion of the tubular member and joined to said portions so that the shell and upper casing section of the housing are supported from the tubular member and a body of filter material confined inside the shell between it and the exterior of the tubular member; and seal members interposed between the upper edge portion of the shell and the adjacent closed end of the upper casing section, and between adjacent portions of the discharge tube and said tubular member for effecting fluid tight seals between the cartridge

and the casing sections upon the application of axial force to the casing sections in a manner drawing said casing sections together.

2. An air cleaner of the character described comprising: an enclosure including substantially coaxial upper and lower cup-like casing sections, the open end of the upper casing section substantially telescoping over the open end of the lower casing section with its rim spaced outwardly of the rim of the lower casing section to provide an annular air inlet for the enclosure; an air discharge tube projecting axially upwardly from the bottom of the lower casing section and opening therethrough to provide for the discharge of cleaned air from the enclosure; a cleaner cartridge in the upper portion of said enclosure including a substantially cylindrical outer shell concentric to but spaced from the sides of the casing sections, said shell having its upper end portion seated against the closed end of the upper casing section so that the same acts to close the upper end of the cartridge, but having its lower open end spaced from the bottom of the lower casing section, a tubular member extending centrally through the cartridge to provide an axial air passage leading from the closed upper end of the cartridge to the lower end thereof, said tubular member having its lower end portion received on the upper end of the discharge tube to be supported thereby and to form an upward extension thereof, circumferentially spaced struts within the shell extending inwardly and downwardly from the juncture of the shell and upper casing section toward the lower end of the tubular member, and connections between the lower end of the tubular member and the adjacent ends of the struts by which axial force exerted on the upper casing section in a manner to draw the sections together is translated directly through the struts into an axial force on the lower end of the tubular member to firmly seat the same on the upper end of the discharge tube; and means at the juncture between the discharge tube and said tubular member placed in compression when the casing sections are drawn together for effecting a fluid tight seal between the discharge tube and said tubular member.

3. In an air cleaner of the type having a housing provided by separable coaxial upper and lower cup-like casing sections having their open ends substantially telescoped together, the bottom of the lower casing section having a standpipe projecting upwardly therefrom into the interior of said lower casing section with said pipe opening through the bottom of the section to provide for the discharge of cleaned air from the housing, a unitary cleaner cartridge comprising: an outer cylindrical shell rolled up from a substantially rectangular blank of sheet metal; a tubular member inside the shell and coaxial therewith; circumferentially spaced diagonal spacing struts rigidly fastened to the shell adjacent to the upper end portion thereof and engaged with the tubular member to space the same concentrically with the shell; a body of filter material between the concentric walls of the tubular member and the shell, said cartridge being adapted to fit within the housing with the lower end portion of the tubular member resting on the upper extremity of the standpipe to form a continuation thereof, whereby the standpipe supports the cartridge in the upper portion of the housing; and centering lugs on said spacing struts adjacent to the lower end of the tubular member engageable with the exterior of the

standpipe when the cartridge is installed within the housing for centering the cartridge with respect to the housing and for assuring alignment of said tubular member with the standpipe.

4. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer substantially cylindrical shell; a tubular member inside the shell and coaxial therewith; circumferentially spaced diagonal spacing struts connecting substantially radially between one end portion of the shell and the tubular member at the opposite end of the shell for joining the tubular member to the shell; a body of filter material between the concentric walls of the tubular member and the shell and in which the spacing struts are embedded, said cartridge being adapted to fit within the enclosure with the shell substantially coaxial with the cup-like casing sections and with said opposite end of the shell lowermost so that the lower end portion of the tubular member bears against the upper portion of the standpipe to form a continuation thereof, whereby the standpipe supports the cartridge in the upper portion of the enclosure; and lugs on said spacing struts engageable with the exterior of the standpipe when the cartridge is installed within the enclosure for centering the cartridge with respect to the lower casing section to thereby assure axial alignment of said tubular member with the standpipe.

5. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer cylindrical shell; an inner tubular member inside the shell and coaxial therewith; an annular shoulder on the exterior of said tubular member adjacent to one end thereof; a sealing washer encircling said end of the tubular member outwardly of said shoulder thereon but lying against said shoulder; spacers carried by the shell and extending radially inwardly from the shell with their inner extremities disposed alongside the shoulder on the tubular member; jaws on said extremities of each of the spacers engaged around said shoulder and the sealing ring to hold the ring firmly against the shoulder and to thereby join the tubular member to the shell; a body of filter material between the concentric walls of the tubular member and the shell, said cartridge being adapted to fit within the enclosure with the sealing ring bearing against the upper end portion of the standpipe to provide a sealed joint between the standpipe and the tubular member with the latter forming an upward extension of the standpipe; and means on said extremities of the spacers engageable with the exterior of the standpipe when the cartridge is installed within the enclosure for centering the cartridge with respect to the enclosure to thereby assure proper seating of the sealing ring on the standpipe.

6. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer cylindrical shell rolled up from a substantially rectangular blank of sheet metal and crimped at spaced points to provide circumferentially spaced longitudinal folds projecting from the exterior of the shell; a tubular member inside the shell and coaxial therewith; substantially flat radial spacers inside the shell with their outer marginal portions clinched between the side walls of said longitudinal folds so as to be carried by the shell and having their inner extremities disposed alongside one end portion of the tubular member; an annular shoulder on said end portion of the tubular member; a sealing ring encircling the tubular member between said end thereof and the shoulder and lying against said annular shoulder; jaws on said inner extremities of the radial spacers engaged over said annular shoulder and the sealing ring for joining the tubular member to the shell and holding the sealing ring firmly against said shoulder; and a body of filter material between the concentric walls of the tubular member and the shell, said cartridge being adapted to fit within the enclosure with said opposite side of the sealing ring bearing against the upper extremity of the standpipe so that the tubular member forms an upward extension of the standpipe, and said longitudinal folds extending from the exterior of the shell acting to guide the cartridge into place within the lower casing section to assure proper positioning of the sealing ring on the standpipe.

7. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer cylindrical shell rolled up from a substantially rectangular blank of sheet metal and crimped at spaced points to provide circumferentially spaced longitudinal folds projecting from the exterior of the shell; a tubular member inside the shell and coaxial therewith; substantially flat radial spacers inside the shell with their outer marginal portions clinched between the side walls of said longitudinal folds so as to be carried by the shell and having their inner extremities disposed alongside one end portion of the tubular member; an annular shoulder on said end portion of the tubular member; a sealing ring encircling the tubular member between said end thereof and the shoulder and lying against said annular shoulder; jaws on said inner extremities of the radial spacers engaged over said annular shoulder and the sealing ring for joining the tubular member to the shell and holding the sealing ring firmly against said shoulder; a body of filter material between the concentric walls of the tubular member and the shell, said cartridge being adapted to fit within the enclosure with said opposite side of the sealing ring bearing against the

upper extremity of the standpipe so that the tubular member forms an upward extension of the standpipe, and said longitudinal folds extending from the exterior of the shell acting to guide the cartridge into place within the lower casing section to assure proper positioning of the sealing ring on the standpipe; a gasket overlying the end portion of the shell opposite the sealing ring; and lugs on said spacers overlying said gasket to hold the same assembled with the cartridge in said position overlying said end of the shell.

8. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer substantially cylindrical shell; a tubular member inside the shell and coaxial therewith; circumferentially spaced struts connecting substantially radially between one end portion of the shell and the tubular member at the opposite end of the shell for joining the tubular member to the shell, a body of filter material between the concentric walls of the tubular member and the shell, said cartridge being adapted to fit within the enclosure with the shell substantially coaxial with the cup-like casing sections and with said opposite end of the shell lowermost so that the lower end portion of the tubular member bears against the upper portion of the standpipe to form a continuation thereof, whereby the standpipe supports the cartridge in the upper portion of the enclosure; and lugs on the opposite end portions of the struts engageable with the exterior of the standpipe and with the upper casing section to hold the casing sections in axial alignment with the cartridge centered with respect thereto and to thereby assure proper seating of the tubular member on the standpipe.

9. In an air cleaner of the type having an enclosure provided by separable coaxial upper and lower cup-like casing sections having their open ends substantially telescoped together, the bottom of the lower casing section having a standpipe opening therethrough and extending axially upwardly into said lower casing section to provide a discharge duct through which cleaned air is discharged from the enclosure, a unitary cleaner cartridge comprising: an outer cylindrical shell rolled up from a substantially rec-

5 55 10 15 20 25 30 35 40 45 50 55

tangular blank of sheet metal and crimped at spaced points to provide circumferentially spaced longitudinal folds projecting from the exterior of the shell; a joint between the ends of the rolled up blank also forming a longitudinal fold projecting from the exterior of the shell; a tubular member inside the shell and coaxial therewith; substantially flat radial spacing struts inside the shell with their outer marginal edge portions clinched between the side walls of said longitudinal folds so as to be carried by the shell and cooperating with the longitudinal folds to reinforce the shell, the inner extremities of said radial spacing struts lying alongside one end portion of the tubular member; means on said end portion of the tubular member providing an annular shoulder projecting from the exterior of the tubular member; a sealing ring on said end portion of the tubular member having one face lying against said shoulder and its opposite side facing the extremity of said end portion of the tubular member; means on said inner extremities of the radial spacing struts engaged with said shoulder and sealing ring for joining the tubular member to the shell and holding the sealing ring firmly against said shoulder; and a body of filter material between the concentric walls of the tubular member and the shell, said cartridge being adapted to fit within the enclosure with said opposite side of the sealing ring bearing against the upper extremity of the standpipe so that the tubular member forms an upward extension of the standpipe, and said longitudinal folds extending from the exterior of the shell acting to guide the cartridge into place within the lower casing section to assure proper positioning of the sealing ring on the standpipe.
